UNITED STATES PATENT OFFICE.

EDWIN M. CARHART, OF PROVIDENCE, RHODE ISLAND.

BURGLAR-ALARM.

SPECIFICATION forming part of Letters Patent No. 410,683, dated September 10, 1889.

Application filed December 26, 1888. Serial No. 294,678. (No model.)

To all whom it may concern:

Be it known that I, EDWIN M. CARHART, a citizen of the United States, residing at Providence, in the county of Providence and State 5 of Rhode Island, have invented certain new and useful Improvements in Short-Circuit Springs for Electrical Alarms; and I do hereby declare the following to be a full, clear, and exact description of the invention, such 10 as will enable others skilled in the art to which it appertains to make and use the same, reference being had to the accompanying drawings, and to letters or figures of reference marked thereon, which form a part of this 15 specification.

My invention relates more particularly to short-circuit springs for electrical alarms; and it consists, essentially, of an electrically-connected shell or casing having a spring-actuated 20 contact-pin mounted therein, combined with an electrically-connected metallic plate insulated from the shell and having an enlarged opening, through which an end of the pin extends, the whole when mounted being so arranged 25 that the pin and contact-plate are insulated from each other when in the normal position. A place well adapted for the use of my improvement is, say, a door leading to a room or vault in which valuables are kept, in 30 which case the electrically-connected shell and plate are mounted in the door-frame, an end of the pin extending through (but not touching) the plate and bearing against an edge of the closed door. Now, in the event 35 of the door being opened the pin is instantly forced into engagement with the contact-plate through the medium of the spring, thereby closing the electric circuit and automatically turning in an alarm at the station or head-quarters. 40

In the accompanying sheet of drawings, Figure 1 represents in reduced scale a complete circuit, in which two doors are electrically connected. It also indicates an office or head-quarters-station, in which a galvanometer is 45 mounted. Fig. 2 is a sectional view taken through the center of my improved short-circuit spring connection, the several parts being in the normal position. Fig. 3 is a similar view of the parts, the door being open and the center contact pin or spindle being in en-

gagement with the electrically-connected plate, thereby closing the circuit and by means of suitable connections located in the main circuit sounding an alarm or otherwise 55 indicating that the continuity of the circuit is interrupted; and Fig. 4 is a front view of the contact-plate.

Referring again to the drawings, A designates my present improvement as a whole. 60 *a* indicates the metallic tubular shell, of brass or other suitable metal, open at the front end and closed at the other. A pin *c* is mounted within the shell *a*, the same extending through the rear end of said shell, and is provided with 65 a stop *c*². Intermediate of the ends of the pin *c* is formed an enlargement or metallic piston *c*', which fits the bore of the tube. The front portion of the piston is substantially cone-shaped, and terminates in the 70 plain portion of the pin, which extends through the contact-plate about to be described. An inclosed spiral spring *e*, engaging the rear end of the shell and at the same time bearing against the under side of the piston, acts to 75 force the pin forward to engage the contact-plate, thereby automatically closing the electric circuit. A stop *c*² serves to limit the forward movement of the pin. In the construction of the shell *a*, I preferably enlarge the 80 front end thereof, so as to form a circular flange *h*, thereby readily adapting it to be electrically connected with one of the conducting-wires *w*; or the wire may be soldered to the shell. 85

b indicates the contact-plate, made of suitable conducting material, as brass, &c., the same having an enlarged central hole *b*' therein, through which the reduced front portion of the pin *c* freely passes, (see Fig. 2,) although 90 permitting the cone-shaped portion *c*' to engage the plate, as shown in Fig. 3, whenever the door or restraining element is removed. Screws passing through holes formed in the extremities of the plate *b* afford means for 95 attaching it to a door-frame, &c., as *d*². By referring to Figs. 3 and 4 it will be seen that the said plate is so formed that it may be readily let into a door-frame, &c., by simply boring shallow holes therein with bits having 100 a corresponding size; or the plate may be circular, as indicated by the broken line *b*³.

(See Fig. 4.) The casing itself may be also as readily attached to the door-frame by boring a hole m therein, the same being enlarged or counterbored at its outer end or face, as 5 m' , to form a seat for the flange h of the shell, as clearly shown. The counterbored portion m' of the hole also forms a non-conducting space or chamber intervening between said shell and the plate, thereby insulating the 10 parts from each other.

The manner of operation is substantially as follows, assuming the shell and plate to be mounted in a door-frame, as d , and connected each with a conducting-wire w , and having 15 the outer end of the pin or piston-rod c passing loosely through the plate b , and being in engagement with and pressing against the door d , as shown in Fig. 2, the electric circuit thus being open: Now, upon opening the 20 door or otherwise removing the pressure from the end of the pin, the spring e instantly acts to force the piston and pin endwise until the enlarged portion of the latter engages and is arrested by the contact-plate b , as shown in 25 Fig. 3. At the instant of the engagement of the parts c and b the continuity of the electric circuit is affected, thereby causing an alarm to be sounded; or the result may be indicated by a corresponding movement of the 30 pointer of a suitably-mounted galvanometer g , located in the circuit.

I would state that the two poles or conducting-wires w may be connected with and form a part of a burglar-alarm system having 35 a headquarters or station communicating with a series of buildings or rooms, in which the several doors and windows thereof are provided with my improvement.

It is obvious that the arrangement of the 40 conducting-wires, battery, &c., may be such that my improved short-circuit spring can be efficiently used either for an open or closed circuit.

I claim as my invention—

1. A short-circuit spring for burglar-alarms, 45 consisting of an electrically-connected shell or casing, a spring-actuated contact-pin provided with a cone-shaped head mounted within the shell, and an electrically-connected plate provided with an enlarged central opening 50 through which the outer end of said pin slightly extends, thereby, when in its normal position, forming an annular space around the pin, substantially as hereinbefore described, and for the purpose set forth. 55

2. The combination of a mounted electrically-connected shell or casing, a spring-actuated contact-pin having its outer or free end provided with a cone-shaped head mounted within the shell, and an electrically-connected 60 plate having an enlarged opening formed therein transversely to receive the head of said pin, and having the plate insulated from the adjacent end of the casing by means of an air-space m' , substantially as described. 65

3. The combination, with the electrically-connected shell a and apertured plate b , constructed and arranged substantially as shown and described, of the spring-actuated contact-pin c , having a cone-shaped head portion 70 extending slightly through said plate, and forming, when thus in its normal open-circuit position, an annular space around the pin, but when the pressure upon the pin is removed the spring forces the head of the pin 75 into engagement with the plate, thereby closing the circuit, substantially as hereinbefore set forth.

In testimony whereof I have affixed my signature in presence of two witnesses.

EDWIN M. CARHART.
